UNITED STATES PATENT OFFICE.

JOSEPH S. LACH, OF BRIDGEPORT, CONNECTICUT, ASSIGNOR TO THE YALE & TOWNE MANUFACTURING COMPANY, OF STAMFORD, CONNECTICUT.

LOCKING DEVICE.

Application filed August 19, 1925. Serial No. 31,215.

This invention relates to improvements in locking devices and more particularly to those of the rim latch type,—one object of the invention being to provide a simple rim latch and door bolt construction.

A further object is to combine with a rim door bolt, means whereby night latch functions may be obtained.

A further object is to so construct the device that reversal of the bolt may be effected to adapt the same to doors differing in bevel.

A further object is to provide simple means to attach the cover plate to the casing without the use of screws.

With these and other objects in view, the invention consists in certain novel features of construction and combinations of parts as hereinafter set forth and pointed out in the claims.

20 In the accompanying drawings;

Figure 1 is a view showing the application of my improvements;

Figure 2 is a horizontal sectional view with the parts assembled on a door and with the keeper applied to the jamb of the door frame;

Figure 3 is a rear or inner view of the rim bolt structure, showing the application of the cover plate to the casing;

Figure 4 is a rear or inner face view with the cover plate removed;

Figure 5 is a similar view with the slide member removed;

Figure 6 is a transverse sectional view on the line 6—6 of Figure 3, and

Figure 7 is an inner face view of the cover plate and rollback cam carried thereby.

A casing 1 for the accommodation of a door bolt 2 and operating means therefor, is secured to the inner face of a door 3 and a strike or keeper 4 for the bolt, is secured to the door jamb 5. The casing 1 is formed with a longitudinal hollow enlargement 6 in which the bolt 2 is movable. The forward end of the bolt is beveled as at 7 and passes freely through a hole in one end of the casing so that it may enter the keeper. The rear end of the bolt terminates in a shank 2^a which passes freely through a hole in the rear wall of the casing and surrounding said shank is a spring 8 operable to project the bolt. The portion 6 of the casing is provided with an elongated slot 9, at the inner end of which, an offset opening, notch or recess 10 is formed, and at the outer or forward end of said slot, a lateral notch or recess 11 is provided,—said slot

and the laterally projecting portions thereof of being intended for the accommodation of an inside knob 12 attached to the bolt 2. By means of the inside knob 12, the bolt may be retracted and it may be held in retracted position by causing the knob to enter the lateral notch or recess 11, or it may be deadlocked in projected position by causing the knob to enter the offset notch or recess 10. The knob 12 is made with a shank 13 which passes transversely through the bolt and projects somewhat beyond the same to form a pin 14 for a purpose hereinafter explained. The projecting pin portion of the knob shank is made with an annular groove 15 which receives a slotted latch plate 16, the latter resting on the bolt 2 and provided with a finger 17 having a toe 18 to engage shoulder 19 formed by an annular groove 20 in the bolt. The latch device serves to latch the knob 12 to the bolt. By removing said latch, the knob may be withdrawn and the bolt given a half turn to adapt its beveled forward end to a door of a different bevel,—after which the knob will be replaced and secured in place by means of the latch device 16—18.

A transversely curved slide 21 is mounted on the bolt 2 and provided with a diagonal slot 22 which receives the pin 14 on the knob shank. The slide 21 is provided intermediate of its ends with lateral arms 23—24, each having a flange 25 at its free end to cooperate with the cover plate 26 of the casing and retain the slide in proper relation to the bolt. A pin 27 projects from the arm 23 of the slide, and the latter is provided at one end with a lateral arm 28, from which a pin 29 projects.

The cover plate 26 is provided at its side edges with resilient flanges 30 which enter the casing 1 and are provided with small bosses 31 which cooperate with ribs 32 with which the side walls of the casing 1 are provided, and thus the cover plate is held in place in the casing without necessity for the employment of screws. The cover plate may also be provided with a guide lug 32^a for the bolt 2.

The door 3 is provided with a suitable bore for the accommodation of a cylinder lock 33, the outer end of which is seated in an escutcheon 34 on the outer face of the door, and screws 35 secure said lock to a plate 36 on the inner face of the door. The operating bar 37 attached to the revoluble member of the lock 33 enters a slot 37^a in the hub 38 of a roll-back cam 39 carried by the cover plate 110

26. The roll-back cam is cooperable with the pins 27 and 29 for controlling the operation of the bolt by the outside key controlled lock means.

5 It is apparent that the bolt may be manually operated from the inside by manipulation of the knob 12, and that it may be also retracted from the outside with the use of a key, even though the bolt be deadlocked in 10 projected position. The bolt may also be released from the deadlocked retracted position, then projected and deadlocked from the outside by the use of the key.

Assuming that the bolt is deadlocked in 15 projected position by reason of engagement of the knob 12 in the lateral recess or offset portion 10 of the slotted casing 1, the operator will insert a proper key in the cylinder lock and impart thereto a double turn,—viz, 20 two rotations in the same direction. During the first rotation of the roll-back cam 39, said cam will engage the pin 29 on the slide 21 and cause longitudinal movement of the latter. During such movement of the slide, the 25 bolt will, by reason of the pin-and-slot connection 14—22, be partially retracted and turned sufficiently to move the knob 12 from the offset opening or notch 10 to the slot 9, and the pin 27 on the slide will be brought 30 within the path of the movement of the roll-back cam because, after cam 39 passes pin 29, spring 8 can project the bolt 2 only to one end of slot 9, at which time, pin 27 will be within reach of the cam 39. During the second 35 turning of the key and the roll-back cam, the latter will engage the pin 27 and move the slide rearwardly, the bolt moving with it and becoming fully retracted. The bolt may be held in retracted position by 40 manually causing the knob 12 to enter the notch or recess 11 in the casing.

The bolt may be deadlocked in projected position by manipulating the key from the outside. This may be accomplished by giving 45 the key a reverse turn, thus causing the roll-back to engage one of the pins on the slide and move the latter forwardly, thus causing the bolt to turn (by reason of the pin-and-slot construction 14—22) and the inside knob 12 to become disposed in the offset opening or recess 10, thereby deadlocking the bolt.

My improvements provide a rim door bolt action combined with a night latch operation.

Various changes might be made in the details of construction of my invention without departing from the spirit thereof or limiting its scope, and hence I do not restrict 60 myself to the precise details herein set forth.

Having fully described my invention what I claim as new and desire to secure by Letters-Patent, is:—

65 1. The combination of a manually operable bolt, means for deadlocking the same,

outside key-controlled means, a slide mounted on the bolt and cooperating therewith to move the bolt to and from deadlocking position, longitudinally spaced pins on the slide, and a roll-back cam operated by said key-controlled means to successively engage the pins for unlocking and retracting the bolt. 70

2. The combination with a casing having a slot with an offset portion, a spring projected bolt movable in said casing, and a knob attached to the bolt and movable in said slot and the offset portion thereof, of key controlled means operable from outside the door, and means operable by said key controlled means to operate the bolt to move the knob 75 out of said offset portion of the slot and then retract the bolt.

3. The combination with a casing having a slot with an offset portion, a spring projected bolt movable in said casing, and a knob attached to the bolt and movable in said slot and the offset portion thereof, of key controlled means operable from outside the door, and means operable by said key controlled means to operate the bolt to move the knob into said offset portion of the slot 80 and thus deadlock the bolt after it shall have been spring-projected.

4. The combination with a casing having a slot, a spring projected door bolt movable in said casing, and a knob on the bolt and movable in said slot, of outside key-controlled means, and a member intermediate said bolt and key controlled means and operatively connected with both, whereby the bolt may be retracted either manually or with the use of a key, against the resistance of the spring which projects the bolt. 95

5. The combination with a casing having a slot provided with an offset portion, a spring-projected bolt movable in said casing, a knob on the bolt and movable in said slot and in the offset portion thereof, and outside key controlled means, of a slide member intermediate said key controlled means and said bolt, and a pin-and-slot connection between said member and the bolt, the slot of said connection being diagonal, whereby operation of said key-controlled means will effect unlocking and retracting of the bolt or locking of the bolt when in projected position. 105

6. The combination with a casing having a slot provided with an offset portion, a spring-projected bolt movable in said casing, a knob on the bolt and movable in said slot and in the offset portion thereof, and outside key-controlled means, of a slide mounted in said casing adjacent to the bolt, a pin-and-slot connection between said slide and bolt, the slot of said connection being diagonal, a roll-back cam operable by said key controlled means, two pins carried by said slide and spaced apart, said pins being positioned to be engaged successively during successive ro- 110 115 120 125 130

tations of the roll-back cam to effect unlock-
ing and retracting of the bolt.

7. The combination with a casing having
a slot provided with an offset portion, a
spring-projected bolt movable in said casing,
a knob on the bolt movable in said slot and
in the offset portion thereof, and outside key-
controlled means, a slide having pin-and-slot
connection with the bolt, the slot of said con-
nection being diagonal, a roll-back cam oper-
able by the key controlled means, and a pin
on said slide in position to be engaged by
the roll-back cam to move the slide in a di-
rection to turn the same when in projected
position and cause the knob to enter the off-
set portion of the slot and dead-lock the bolt
by manipulation of the key controlled means.
8. The combination with a casing having
a slot provided with an offset portion, a
spring-projected bolt movable in said casing,
a knob on the bolt and movable in said slot
and in the offset portion thereof, and out-
side key controlled means, of a slide mem-
ber intermediate said key controlled means
and said bolt, a pin-and-slot connection be-
tween said member and the bolt, the slot of
said connection being diagonal, whereby op-
eration of said key-controlled means will ef-
fect unlocking and retracting of the bolt or
locking of the bolt when in projected posi-
tion, and guide and retaining means for said
slide member.
9. The combination with a slotted casing
and a door bolt movable therein said bolt

having a beveled forward end, of a knob 35
movable in the slot of the casing and hav-
ing a shank passing transversely through
the bolt and removable therefrom to permit
rotary adjustment of the bolt to adapt the
latter to doors of different bevels.

10. The combination with a slotted casing,
a door bolt movable therein, said bolt hav-
ing a beveled forward end, of a knob mov-
able in the slot of the casing and having a
shank passing transversely through and be-
yond the bolt, and means normally locking
the knob from displacement relative to the
bolt.

11. The combination with a slotted casing,
a door bolt movable therein, said bolt hav-
ing a beveled forward end, of a knob movable
in the slot of the casing and having a shank
passing transversely through and beyond the
bolt, and a removable locking device engag-
ing said shank to lock said shank to the bolt. 50

12. The combination with a slotted casing,
a door bolt movable therein, said bolt having
a beveled forward end, of a knob movable
in the slot of the casing and having a shank
passing transversely through and beyond the
bolt, said shank having a groove and the bolt
having a shoulder, and a slotted locking plate
to engage in the groove in the knob shank,
said plate having a part provided with a toe
to engage the shoulder on the bolt. 55

In testimony whereof, I have signed this
specification.

JOSEPH S. LACH.
